UNITED STATES PATENT OFFICE.

CHRISTIAN HÜLSMEYER, OF DÜSSELDORF, GERMANY.

WIRELESS TRANSMITTING AND RECEIVING MECHANISM FOR ELECTRIC WAVES.

No. 810,150

Specification of Letters Patent.

Patented Jan. 16, 1906.

Application filed March 14, 1904. Serial No. 198,075.

To all whom it may concern:

Be it known that I, CHRISTIAN HÜLSMEYER, a subject of the German Emperor, residing at Düsseldorf, Germany, have invented a certain new and useful Improvement in Wireless Transmitting and Receiving Mechanism for Electric Waves, of which the following is a specification.

The object of this invention is to provide apparatus by which the further application of electrical waves may be had not only to the transmission of communications, but may also be had for actuating mechanism placed at distance, for instance closing circuits and releasing clockworks &c., for the purpose of turning on and off all kinds of lights, the lighting of mines, for putting motors into and out of circuit, for the service of gates, switches or signaling on railways. And in all such cases it is necessary that no other waves save those from the proper transmitter should ever actuate or in any manner affect the working of the same. This I accomplish by my invention which consists of a transmitting apparatus constructed in such manner that the length of the waves may be varied at will and in which the sensibility of the coherer may be also regulated, each transmitting and receiving apparatus being provided with synchronized clock mechanism, which rotate insulated contact-wheels, connected by one or more contact-pieces to conductor arranged at intervals around them; the contact-wheel of the transmitter having a single current which is furnished with a determined time-scale, and upon which one or more contacts are slidably arranged. It thus is possible to actuate, with a single transmitter, as many receiving apparatus, independently one of the other, as time variations may be combined upon the scale on the transmitter with the aid of the contacts. Other means of regulation is afforded by mechanism for varying the length of the electric waves and the sensibility of the coherer. The possibility of regulating the latter is a principal condition for the sure working of the apparatus. The forms known for this purpose need to be regulated by the hand of man. In the present construction of the coherer the sensibility is regulated to a previously-determined degree and the coherer always returns in an automatical manner to the desired sensibility.

My said invention is fully shown and described in the following specification, of

which the accompanying drawings form a part, wherein like letters of reference designate like or equivalent parts wherever found throughout the several views, and in which:—

Figure 1 is a diagrammatic view of my improved wireless transmitting apparatus; Fig. 2 is a like view of my improved receiving apparatus usually used in connection with the transmitter shown in Fig. 1; Fig. 3 is a diagrammatic view of my improved form of regulatable and self-regenerating coherer and the mechanism connected therewith; Fig. 4 is a side view in vertical section of the battery of receiving-wires when of the angular or rectangular construction, and Fig. 5 is a view of the construction shown in Fig. 4 taken in horizontal cross-section; Fig. 6 is a diagrammatic view of the arrangement of the receiving-wires when the same is cylindrical; and Fig. 7 is a diagrammatic view in elevation partially in section of the coherer and clockwork at the receiving-station, and the mechanisms connected therewith.

Referring to the drawings:—I will now describe in detail the construction of the device conjointly with a description of the functions of the various parts of the mechanism, which being mostly shown diagrammatically and therefore need little if any description as the construction thereof is self-evident from a mere inspection of the drawings.

When the key A' of the transmitter (Fig. 1) is pressed down, the current of the battery A² flows from the insulated contact-wheel A³, which is actuated by a synchronous clock-motion (not shown) and which is provided with a contact-brush A⁴ and a stop-lug A⁵, from the latter through the spring stop-lever A⁶ and the guide A⁷, round the electromagnet A⁸, and through the primary coil A⁹ into the inductorium and returns through the key to the battery. The high-tension current of the secondary coil A¹⁰ is conducted to one coating of two condensers A¹¹ and A¹², the other coating of which is connected to the oscillator A¹³. The electric waves sent from the oscillator are received by the antenna B' of the coherer. The current of the battery B³ then circulates around the coil of the electromagnet B⁴ and reaches the contact-wheel B⁵, which is rotated in the same manner as A³; and synchronously therewith the current then passes through the contact B⁶, the spring-lever B⁷, through the conductor B⁸, the coherer B⁹ and returns to the battery B³;

and the lever B⁷ decoheres the coherer B after the passage of the wave. At the moment of closing the circuits in the transmitter as well as in the receiver, both contact-wheels A³ and B⁶ are released, at the same instant by the attracting electromagnets A⁸ and B⁴ and rotate synchronically in the direction of the arrows.

Round the contact-wheel A³ of the transmitting apparatus (Fig. 1) is arranged a contact-ring A¹⁴ provided with a time-scale and a slot, in which slides a contact A¹⁵, and it is evident that instead of one there may be several contacts. The contact-wheel B⁶ of the receiving apparatus (Fig. 2) is also surrounded by contact-rings which are separated and insulated from each other. When the contact-brush A⁴ of the contact-wheel A³ has reached the contact A¹⁵ of the contact-bar A¹⁴, B⁶ has reached, at the same moment, the movable contact B⁹. The second closing of the circuit effected in the transmitting apparatus Fig. 1 and the second wave impulse, thus produced, the coherer is put in circuit and the current of the battery B³ flows therefrom around the coil of the electromagnet B⁴, on the contact-wheel B⁶, over the contacts B⁶ and B⁹, by the conductor B¹⁰, to the place where it is employed, either for lighting mines, for electromechanically closing circuits for any industrial purpose, or for releasing contacts, &c. The current, after having accomplished its mission, returns of course to the battery B³ by way of the conductor B¹¹ and the coherer B².

In order to prevent electric waves intended for the transmission of news or for any other purpose, or coming from a non-authorized person having the intended effect, the contact-wheel B⁵ of the receiving-post is surrounded by bars B¹² arranged between the contacts. These bars being electrically connected together and to an electromagnet B¹³. When the electric waves do not reach the coherer in the period and the order corresponding to the construction of the receiver, the current of the local battery B³ passes from the contact-wheel B⁵, over the contact B⁶, over the bar B¹², around the coil of the electromagnet B¹³, and attracts the lever B¹⁴, which is provided with an armature, and thus removes the contact B⁹, out of the contact way of the contact-wheel B⁶. When the contact B⁶ of the contact-wheel has passed the gap of the contact B⁹, the latter is automatically pushed back and returned to its original position by the contact-wheel B⁶, as well as by the insulated lever B¹⁵. This operation is repeated until the electric waves reach the coherer in the predetermined manner. It is therefore quite impossible for any one who has no sender analogous and electrically attuned to the receiver to actuate the latter in an efficient manner.

To obtain an exact operation of the re-

ceiver, it is necessary that the coherer work according to the more or less strong waves of the transmitting-post, and that the resistance of the coherer-powder is diminished in such a manner that the electromagnets work correctly. As the resistance after each interruption by the striker is very different, it is necessary to fix this resistance and to allow the coherer to regulate itself automatically to this resistance. This is obtained in the following manner. In a vacuum glass tube C, are arranged two metal pistons C² and C³ of which C² is fixed, while C³ is movably suspended to a wire coil; between the pistons is contained the coherer-powder, in the present instance graphite usually mingled with metal powder. The glass cylinder is supported upon a support C⁵, oscillating on an axis C⁴, and is more or less inclined by a system of levers C⁶, connected to the end of C⁵. The levers are influenced by a solenoid C⁷, around the coil of which circulates a local current, and by a counterweight C⁸. According to whether the end of the coherer with the piston C³ is pulled up or down by this system of levers, the movable piston, which is suspended to the spring will, owing to its proper weight press more or less upon the coherer-powder, and produce in this manner a more or less intimate contact. The local current traversing the coherer and the solenoid in the inactive state, ought to be strong enough to balance the counterweight C⁸. When the weight C⁸ is increased, the resistance of the coherer is diminished, by reason of the inclined position, and the lowering of the piston C³. When the weight is diminished, the resistance increases. When the coherer has been regulated for a determined resistance, and, when waves strike the antenna C⁹, they are transmitted from the primary coil C¹⁰, to the secondary one C¹¹ of the local circuit, and actuate the coherer the resistance whereof lowers. The Morse apparatus or telephone with striker (not shown) inserted in this circuit are then actuated and the coherer returns to its former degree of resistance. This operation is repeated after each transmission of a sign.

As for the manipulation of the apparatus, a compact and squat form is advantageous, plates of resisting and insulating material, which are traversed by the receiving-wires, are provided in the recessed sides of the casing. For quadrangular forms Figs. 4 and 5, each side is reunited so as to form a single group of wires. The wires meet at a common introduction-point D', are all of the same length and reach the coherer inclosed in the casing. Each of the wire plates may be dismounted by means of the screws D². For circular or cylindrical forms (Fig. 6), it is advisable to embed the receiving-wires E in an umbrella form in the insulating-lining E² surrounding the casing E' and to give all the

wires a common entry from above. In all forms however, the other end E⁴ of the coherer is connected with the base-plate of the casing and serves as lead to earth.

5 Having now fully described my invention, what I claim, and desire to secure by Letters Patent, is—

1. In a device of the kind described the combination with an electric-wave transmitter, of an electric-wave receiver, each having synchronously-rotating contact-wheels, for automatically freeing the contact-wheels, means for actuating the receiver mechanism, after a predetermined space of time, means 10 for preventing all other waves arriving at other moments actuating the receiver mechanism, and means for regulating the resistance of the coherer to a determined point, by varying the angle of the coherer, substantially as and for the purpose described.

2. In an electric-wave transmitter, the combination with the primary circuit of the inductorium and a manipulating-key, of an electromagnet inserted in the said circuit and 25 actuating a spring stop-lever, a contact-wheel inserted in the said primary circuit, a stop-lug integral with the contact-wheel and in electrical contact with the said spring-lever when at rest, and completing the primary circuit, a contact-piece on a contact-ring surrounding the contact-wheel and connected to the primary circuit, which it completes through the contact-wheel, when the lug of the latter, during the rotation touches the 35 contact-piece of the contact-ring, and means for varying the moment at which the primary circuit is closed during the rotation of the contact-wheel, substantially as and for the purpose described.

3. In an electric-wave transmitter, the combination with the primary circuit of the inductorium and a manipulating-key of an electromagnet, inserted in the said circuit and actuating a spring stop-lever, a contact-wheel inserted in the said primary circuit, a stop-lug integral with the contact-wheel and in electrical contact with the said spring-lever when at rest, and completing the primary circuit, a contact-piece slideable and fixable in circular groove of a contact-ring, surrounding the contact-wheel and connected to the primary circuit, which it completes through the contact-wheel when the lug of the latter during its rotation, touches the contact-piece, the contact-ring being provided with a time-scale, substantially as and for the purpose described.

4. In an electric-wave receiver, the combination with a coherer-circuit of an electromagnet inserted in the coherer-circuit and acting upon a stop-armature, a contact-wheel rotating synchronously with the contact-wheel of the transmitter, and inserted in the coherer-circuit, by means of a stop-lug in contact with the said stop-armature when

the contact-wheel is at rest, a movable contact disposed at a place corresponding to that of the contact-piece of the transmitter, and completing the circuit of the receiving apparatus, when the lug of the contact-wheel touches it during the rotation of the wheel, and means for removing the said contact out of the way of the said contact-lug when electric waves arrive at other moments than those corresponding to the closing of the contacts of the transmitter and receiver, substantially as and for the purpose described.

5. In an electric-wave receiver, the combination with a coherer-circuit of an electromagnet inserted in the coherer-circuit and 80 acting upon a stop-armature, a contact-wheel rotating synchronously with the contact-wheel of the transmitter, and inserted in the coherer-circuit by means of a stop-lug in contact with the said stop-armature when the 85 contact-wheel is at rest, a movable contact disposed at a place corresponding to that of the contact-piece of the transmitter and completing the circuit of the receiving apparatus, when the lug of the contact-wheel touches it 90 during the rotation of the wheel, and electrically-connected contact-pieces surrounding the contact-wheel and completing by means of this contact-wheel and its contact-lug, the circuit of an electromagnet, inserted in the 95 coherer-circuit, when electric waves arrive at other moments than those provided for by the adjustment of the apparatus, the said electromagnet by its armature withdrawing the movable contact from the way of the lug 100 of the contact, and a lever, operated by the contact-lug, when the latter has passed the movable contact, substantially as and for the purpose described.

6. In a coherer for electric-wave receivers 105 of the kind described, the combination with a glass vacuum-tube of a fixed piston, a movable piston, a body of coherer-powder located between the pistons, a suspension-spring for the movable piston within the tube, and means for inclining the glass tube to different angles so as to vary the pressure of the movable piston upon the body of coherer-powder, substantially as and for the purpose described.

7. In a coherer for electric-wave receivers 115 of the kind described, the combination with a glass vacuum-tube, of a fixed piston and a movable piston containing between them a body of coherer-powder, a suspension-spring for the movable piston, a balancing support-plate, a lever system inclining more or less the said balancing support-plate, a solenoid-armature connected to the said lever system, and a counterweight also connected to the said lever system and counteracting the action of the said solenoid inserted in the circuit of the coherer, substantially as and for the purpose described.

8. In a receiver for wireless electric apparatus comprising a metallic casing, insulating

plates lodged in the recessed side walls of the casing, receiving-wires embedded in the insulating-plates and connected together at the entry-point of the casing, and a base-plate connected to the other end of the coherer and serving as earth-conductors, substantially as and for the purpose described.

In testimony whereof I have hereunto set my hand in presence of two witnesses.

CHRISTIAN HÜLSMEYER.
